UNITED STATES PATENT OFFICE.

CHARLES K. MORTON, OF CLEVELAND, OHIO, ASSIGNOR TO THE GLENN L. MARTIN COMPANY, OF CLEVELAND, OHIO, A CORPORATION OF OHIO.

AIRPLANE.

Application filed September 18, 1927. Serial No. 219,889.

This invention relates to improvements in airplanes, but has reference particularly to means for adjusting the horizontal stabilizer or any other part of considerable size which 5 it may be desirable to adjust.

One object of the invention is the provision of means which shall render it possible for the pilot or other member of the crew of an 10 airplane to build up gradually, by the use of small manual impulses, the power necessary 15 to make the adjustments above referred to.

Another object of the invention is the provision of means for readily reversing the direction of the adjustment to be performed and 20 for locking the stabilizer or like adjusted part 15 in any desired position.

Other objects and features of novelty will 25 appear as I proceed with the description of that embodiment of the invention which, for 20 the purposes of the present application, I 25 have illustrated in the accompanying drawing, in which

Fig. 1 is a diagrammatic view illustrating 25 a horizontal stabilizer and hydraulic apparatus for adjusting the same, the actuating parts shown mounted upon the instrument board of the plane;

Fig. 2 is a fragmentary front elevation of 30 the instrument board;

Fig. 3 is a detailed view on a larger scale 35 of a fluid pump or compressor which may be employed in connection with the invention, some of the parts being shown in section on the line 3—3 Fig. 1;

Fig. 4 is a side elevation of a power cylinder, the piston of which may be connected 40 with the stabilizer to be adjusted;

Fig. 5 is a longitudinal sectional view taken 45 substantially on the line 5—5 Fig. 4;

Fig. 6 is a central sectional view of a hollow casting enclosing one end of the pump and upon which the valve parts are supported;

Fig. 7 is a similar view of similar parts at 50 the opposite end of the pump;

Fig. 8 is a cross section on the line 8—8 55 Fig. 6;

Fig. 9 is a detailed view on a large scale 60 showing one of the check valves which may be employed;

Fig. 10 is a front elevation of a pair of gear sectors used in controlling the apparatus;

Fig. 11 is an edge view of the same;

Fig. 12 is a view, partly in section, through 65 the instrument board showing the means for 70 actuating the shaft upon which the upper 75 pair of sectors are mounted; and

Fig. 13 is a face view of the operating handle shown in Fig. 12 with its extreme positions indicated by dotted lines.

In the drawing, fragments of the airplane 80 frame work are shown at 10 and 11. To this frame work is hinged at 12 a stabilizer 13, while an elevator 14 is hinged to the rear end of the stabilizer. A link 15 connects the stabilizer near its forward or free end to a 85 piston rod 16 carrying a piston 17 that moves in a power cylinder 18 secured to the frame work of the plane. From the upper end of the cylinder 18 a tubular conductor 19 extends forward to the cockpit of the plane, and a 90 similar conductor 20 extends forward from the lower end of the cylinder.

While in its broader aspects my invention is 95 independent of any particular type of pump or compressor, I prefer to employ a double-acting piston pump as shown in the drawing. The pump cylinder 21 is mounted by any suitable means directly in advance of the instrument board 22 on the plane. The piston 23 is mounted at the end of a piston rod 24 80 which projects through one end of the pump and through an opening in the instrument board 22, being provided at its outer extremity with a handle 25 by means of which the piston may be manually reciprocated. 85

The cylinder 21 is closed at its rear end by a hollow casting 26 which is separated into two compartments by a dividing wall 27. At the opposite end of the cylinder there is a similar hollow casting 28 with a dividing wall 90 29. The upper and lower chambers of the casting 26 have externally threaded bosses 30 and 31, respectively, while the corresponding chambers of the casting 28 have similar bosses 32 and 33. All of these bosses have drilled 95 openings therethrough, and the two upper bosses are connected by a tubular yoke 34 while the two lower ones are connected by a similar yoke 35. The forward ends of the tubular conductors 19 and 20 are attached by 100 suitable unions to yokes 34 and 35, respectively.

Through the inner wall of each of the castings 26 and 28 there are one or more holes 36 above the dividing wall 27 or 29, as the 105 case may be, and a similar number of holes 37 below the dividing wall. A disk 38 closely engages the inner wall of casting 26, the en-

gaging surfaces being machined for that purpose, the disk being held in position by an inturned flange on a ring 39 which is threaded onto the casting. A similar disk 40 is similarly mounted on casting 28 by means of a flanged ring 41. The disks 38 and 40 each have passages therethrough which are adapted to register with the holes 36 and 37 in the casting, when the disk is rotated into either one of two positions 180° apart. Where four holes and passages are employed, as in the form illustrated, two of the passages in each disk are provided with ball check valves 42 opening toward the cylinder 21 and the other two passages with check valves 43 opening away from the cylinder.

The disk 38 is arranged to be rotated by a shaft 44 which is mounted in a bearing formed in a central enlargement of the dividing wall 27, being provided with a threaded end portion of reduced diameter which extends through a central opening in the disk 38, and the latter being clamped in place by a nut 45. The disk 38 is free to rotate with the shaft 44, and in order that oscillation or partial rotation may be imparted to it the shaft 44 carries a gear sector 46 on its outer extremity. The disk 40 mounted upon casting 28 is threaded upon a sleeve 47 and held in position by a lock nut 48. The piston rod 24 extends through this sleeve, and each is movable independently of the other. On its outer extremity the sleeve carries a gear sector 49 substantially identical with gear sector 46 and held in position by nuts 50 threaded upon the sleeve.

The two sectors 46 and 49 mesh with sectors 51 and 52 which are pinned to a rock shaft 53 that extends through the instrument board 22 above the piston rod 24, where it is provided with an operating lever 54. A pair of stops 55 limit the throw of the lever 54. When the latter stands at one limit of its motion the inwardly opening check valves register with the holes in the castings 26 and 28 above the dividing walls and the outwardly opening check valves register with the holes below the dividing walls, while when the lever 54 is thrown to the opposite limit of its motion the inwardly opening valves register with the holes below the dividing walls and the outwardly opening valves with the holes above the dividing walls. In the intermediate position of the lever 54 the holes through the casting walls are closed by the disks.

In Fig. 9 I have illustrated one form of ball check valve which may be employed. The ball 56 is movable within the main portion 57 of the passage through the disk and seats upon the inner end of a reduced portion 58 of the passage, being urged toward its seat by a coil spring 59 which abuts at the opposite end against a ring 60 that is threaded into the disk at the end of the main portion

57 of the passage. The valves 42 and 43 herefore mentioned may be identical with the structure shown in Fig. 9, except that they are reversely arranged in the disks.

Assuming that it becomes desirable to depress the forward edge of the stabilizer 13, pressure fluid must be admitted to the upper end of power cylinder 18 through tubular connection 19, and a corresponding exhaust of fluid must take place from the lower end of cylinder 18 out through tubular connection 20. To this end the lever 54 must be thrown to an extreme position such that the disks 38 and 40 shall be brought into the positions illustrated in Figs. 6 and 7. The sectors 51 and 52 are so proportioned to the sectors 46 and 49, in the present disclosure, that a quarter turn of the former will actuate the latter through half a revolution. The operator then reciprocates the handle 25 until the desired adjustment is reached. As the piston 23 moves toward the left in Fig. 3 the lower right-hand valves 42 open, permitting fluid to enter the cylinder from conductor 20, while the upper left-hand valves 43 open to permit fluid to pass from the cylinder into the conductor 19. As the piston 23 moves in the opposite direction, the lower left-hand valves 42 open permitting fluid to enter the cylinder from conductor 20, while the upper right-hand valves 43 open permitting the piston to force fluid out of the cylinder into conductor 19. The pumping is discontinued after the desired adjustment has been reached, and then the lever 54 is turned into its midway position, thereby carrying the fluid passages in disks 38 and 40 out of register with the holes in the castings 26, 28. Now should it later be desired to elevate the forward edge of the stabilizer, the lever 54 is thrown to the opposite extreme position reversing the arrangement of the check valves and the pump again operated. The movement of pressure fluid in the system is thus reversed and the piston 17 is moved upwardly to an extent proportionate to the operation of the piston 23. When the proper adjustment is reached the lever is again brought back to the intermediate position, thereby cutting off the tubular connections 19 and 20 from each other and also from the pump.

The comparative diameters of the pistons 23 and 17 should, of course, be proportioned to the load put upon the latter by the stabilizer 13 under flying conditions. In the drawing I have made no attempt to illustrate these parts to scale. In fact the piston 17 will be much larger than the piston 23 in order to bring about a power advantage. As pressure fluid I employ oil, but other liquids might be substituted. Air or some other gas might be used, but it is ordinarily preferable to employ a liquid rather than a compressible fluid for this purpose, for the reason that the

liquid will positively hold the stabilizer in adjusted position. If it should be found desirable under some conditions to hold the stabilizer or other adjusted part in position resiliently, then air could be advantageously employed.

Having thus described my invention, I claim:

1. In an airplane, a stabilizer comprising a hinged member, a fluid cylinder located near the free end of said member, a piston therefor connected to said member, a fluid pump, tubular conductors connecting both ends of said cylinder with said pump, and means for connecting the delivery side of said pump to either of said conductors. 50
2. In an airplane, a stabilizer comprising a hinged member, a fluid cylinder located near the free end of said member, a piston therefor connected to said member, a fluid pump, tubular conductors extending from opposite ends of said cylinder to said pump, said cylinder, pump and conductors forming a closed system, and means at the pump for reversing the direction of flow of fluid. 55
3. In an airplane, a stabilizer comprising a hinged member, a fluid cylinder located near the free end of said member, a piston therefor connected to said member, a fluid pump, tubular conductors extending from opposite ends of said cylinder to said pump, said cylinder, pump and conductors forming a closed system, and means at the pump for cutting off one conductor from the other. 60
4. In an airplane, a stabilizer comprising a hinged member, a fluid cylinder located near the free end of said member, a piston therefor connected to said member, a fluid pump, tubular conductors extending from opposite ends of said cylinder to said pump, said cylinder, pump and conductors forming a closed system, and means for disconnecting the pump from both of said conductors. 65
5. In an airplane, a stabilizer comprising a hinged member, a fluid cylinder located near the free end of said member, a piston therefor connected to said member, a fluid pump, tubular conductors connecting both ends of said cylinder with said pump, said cylinder, pump and conductors forming a closed system, and common means for reversing the flow of fluid or for disconnecting the pump from both of said conductors. 70
6. In an airplane, a stabilizer comprising a hinged member, a fluid cylinder located near the free end of said member, a piston therefor connected to said member, a pump cylinder and double-acting piston, a tubular conductor connecting each end of said first named cylinder to both ends of said pump cylinder, valve means at both ends of said pump cylinder for reversing the direction of flow through said pump, and common means for actuating both of said valve means. 75
7. In an airplane, a stabilizer comprising a hinged member, a fluid cylinder located near the free end of said member, a piston therefor connected to said member, a pump cylinder and double-acting piston, a tubular conductor connecting each end of said first named cylinder to both ends of said pump cylinder, valve means at both ends of said pump cylinder for reversing the direction of flow through said pump and for cutting off the pump from said conductors, and common means for actuating both of said valve means. 80
8. In an airplane, a stabilizer comprising a hinged member, a fluid cylinder located near the free end of said member, a piston therefor connected to said member, a fluid pump, tubular conductors extending from opposite ends of said cylinder to said pump, said cylinder, pump and conductors forming a closed system, and said means comprising a rotatable disk carrying a pair of oppositely opening check valves. 85

In testimony whereof, I hereunto affix my signature.

CHARLES K. MORTON.
